[57] **CLAIM**

The ornamental design for a soap dispenser pump tip, as shown and described.

DESCRIPTION

FIG. 1 is a three-dimensional front view of the soap dispenser pump tip showing my new design;
FIG. 2 is a three-dimensional rear view thereof;
FIG. 3 is a front elevation perspective view thereof;
FIG. 4 is a top plan thereof;
FIG. 5 is a bottom plan thereof.
FIG. 6 is a rear elevation perspective view thereof; and,
FIG. 7 is a side plan thereof; all other sides not shown being identical to the side shown.
